ILLUMINATING DEVICE

Filed May 13, 1930

Inventor:
PAUL M. HOTCHKIN
E. R. Murphy, Atty.

UNITED STATES PATENT OFFICE

PAUL M. HOTCHKIN, OF CHICAGO, ILLINOIS, ASSIGNOR TO CURTIS LIGHTING, INC., OF CHICAGO, ILLINOIS, A CORPORATION OF ILLINOIS

ILLUMINATING DEVICE

Application filed May 13, 1930. Serial No. 452,078.

My present invention relates to an illuminating device of the type known as direct-indirect in which indirect illumination is provided by an inverted reflector element that throws the light upwardly from a light source toward the ceiling, and the direct or diffused illumination is secured by means of a shade which encloses or surrounds the reflector and is illuminated to avoid the appearance of a dark object or shadow at the location which the upwardly directed light rays originate.

In the present structure I have provided the portion inside the shade in the form of a unitary structure which is adapted to act both as the reflector for the indirect illumination and as a transmitter or diffuser for the rays that are directed upon the shade which is more or less translucent.

My present invention has been devised with numerous objects in view among which may be mentioned the provision of an illuminating device that is novel in construction, easy to manipulate, dependable in operation, and capable of effecting artistic results.

I prefer to carry out my invention and to accomplish the objects thereof in substantially the manner hereinafter described, as more particularly pointed out in the claim, reference being made to the accompanying drawing that forms a part of this specification.

In the drawing:—

Figure 1 is a vertical side elevation of a lighting fixture of the floor or stand type made in accordance with my invention, the parts at the upper portion thereof being broken away and in section.

Figure 2 is a view similar to the upper portion of Figure 1, partly in section, and showing a modified structure.

Figure 3 is a view similar to the preceding figures showing the upper portion of another modified type of fixture made in accordance with my invention.

The drawing is more or less schematic for the purpose of illustrating typical forms in which my invention may be made, and in said drawing similar reference characters have been employed to designate like parts where-

ever they appear throughout the different views.

Referring more particularly to Figures 1 and 2, it will be seen I have provided a standard or column 5 that has a suitable base 6 and which terminates in a suitably shaped head or top 7. The head or top 7 is preferably cup-shaped and is provided with a shoulder 8 at its upper portion that terminates in an upstanding flange or flare 9. This upper portion of the head provides a seat to receive the exterior shade 10 of the fixture which is preferably hollow and made from translucent or light transmitting material and rests at its lower end upon the shoulder 8 within the flange 9 so that the lower portion of the shade is closed.

A suitable lamp socket 11 is mounted within the lower position of the shade 10 above the head 7 of the column and it is surrounded by a cup-shaped member 12 that is provided upon its upper edge with a seat 13 to receive the light controlling and directing member. An electric light bulb 14 is inserted in the socket 11 and is surrounded by the light control structure which will be later described. The bulb 14 is preferably of a high wattage and the rays of light therefrom are utilized as the sole or only means for securing the indirect illumination that is reflected upwardly and for the diffused direct illumination which is transmitted to the shade 10 by this control structure.

The light controlling and directing structure has its upper section formed so as to provide an inverted bowl-shaped reflector 15 that is surrounded by the shade 10 and is so disposed that the light rays from the bulb striking its mirrored surfaces will be reflected in an upward outward direction to the ceiling from which it is returned to the interior of the room. The lower portion of the reflecting section is formed into a restricted opening 16 that surrounds the tapered portion of the bulb but which is spaced therefrom a distance sufficient to permit light rays from the bulb to travel downwardly through said opening 16.

Below the opening the light control structure consists of a diffuser 17 which is pref-

- erably made from opal-glass or other translucent material which will permit light rays impinging upon its inner surface to be transmitted in diffused form through the same and then be distributed upon the interior surface of the shade 10. As shown in Figures 1 and 2 the diffusing section of the light control structure is formed of glass and made integrally with the reflector section, whereas, in Figure 3 the diffuser section 18 is in the form of a separate cup-shaped part below the reflector and surrounding the opening 16 in the lower portion of the latter. In said Figure 3 the reflector section 15 is supported above the diffuser cup by means of an open frame 19 that extends upwardly from the socket or other portion of the fixture. It is immaterial how the frame is supported.
- 20 In Figure 2 I have shown a structure similar to that illustrated in Figure 1 and in addition to securing the inside illumination of the shade 10 I have also provided brackets or arms 20 extending outwardly from the head 7 of the column and have provided sockets upon the ends thereof in which auxiliary exterior bulbs 21 may be mounted.

25 In all of the forms shown it will be noted the shade is open at its top but its bottom portion is closed so as to prevent direct light rays or diffused light rays from passing out of the fixture in a downward direction.

What I claim is:—

30 A combined direct and indirect lighting fixture comprising a vertical standard, an opaque support arranged substantially horizontally at the upper end of said standard, a translucent shade open at its top and bottom mounted on the rim of said support to close its bottom opening and prevent passage of light rays therethrough, an extension projecting from said standard into said shade, an electric socket on the upper end of said extension, a light bulb in said socket, a translucent light-diffusing bowl supported from said extension and providing the sole means for transmitting light rays from the bulb to the shade, and an inverted opaque reflector above said bowl and surrounding the bulb and adapted to reflect light rays from the latter upwardly out of the fixture.

35 Signed at Chicago, in the county of Cook and State of Illinois, this 30 day of April, 1930.

55 PAUL M. HOTCHKIN.
